United States Patent Office

Des. 185,337
Patented May 26, 1959

185,337

LIPSTICK CASE

Raymond W. Wolff, Bridgeport, Conn., assignor to Helena Rubinstein, Inc., New York, N.Y., a corporation of New York

Application November 26, 1957, Serial No. 48,677

Term of patent 14 years

(Cl. D86—10)

Fig. 1 is a perspective view of a lipstick case, showing my new design;

Fig. 2 is a side elevational view thereof; and

Fig. 3 is a top plan view of the cover portion of the lipstick case.

I claim:

The ornamental design for a lipstick case, substantially as shown.
